BUILDING

Charles W. Tingley, Milwaukee, Wis., assignor to
Josephine A. Tingley and Daniel M. Tingley

Application February 20, 1937, Serial No. 126,854

7 Claims. (Cl. 20—49)

This invention appertains to buildings, and more particularly to window constructions, ostensibly of the sliding sash type.

One of the primary objects of my invention is to provide novel means for mounting the sashes in the window frame, whereby the lower sash can be readily tilted and locked in an adjusted position relative to the sliding upper sash to bring about the thorough and efficient ventilation of a room.

Another salient object of my invention is the provision of means whereby both the upper and lower sashes are freely removable from the window frame, so that the opposite faces of the panes of the sash can be quickly and conveniently cleaned without danger to the operator.

Another important object of my invention is the provision of means whereby the lower sash can be held in a reversed position in the window frame, so that this sash can be held rigid, if so desired, during the washing of the outer face of the window pane.

A further object of my invention is the provision of novel sliding plates upon which the lower corners of the upper sash rest, with means whereby the upper sash can be swung into a room or removed entirely from the frame, or reversed, when the upper sash is in its extreme lowered position.

30 A further important object of my invention is the provision of novel means for detachably holding the slide plates in their lowered position against accidental movement when the upper sash is swung into a room or removed from the slide plates.

35 A further object of my invention is the provision of means for automatically releasing the slide plates when the upper sash is swung back to its vertical normal position, whereby the sash can be freely slid to its raised closed position.

40 A further object of my invention is the provision of novel means for arranging the sashes relative to themselves and to the frame, whereby an air-tight and weatherproof window will be had.

45 A further object of my invention is the provision of novel means for holding the sashes in their various positions so that the sashes cannot be manipulated by persons standing on the outside of the room.

50 A still further object of my invention is to provide a window construction of the above character which will be of an especially simple and durable construction, and which can be incorporated in a new or old building at an economical price.

55 With these and other objects in view, the in-

vention consists in the novel construction, arrangement, and formation of parts, as will be hereinafter more specifically described, claimed, and illustrated in the accompanying drawings, in which drawings:

Figure 1 is a front elevation of a window constructed in accordance with my invention.

Figure 2 is a longitudinal section through the same, taken on the line 2—2 of Figure 1, looking in the direction of the arrows, the sashes being shown in dotted lines only to permit a comprehensive understanding of the guides and slide plates for the sashes to be had.

Figure 3 is an enlarged detail vertical section through the lower sash illustrating the means employed for holding the sash in an adjusted position.

Figure 4 is a detail sectional view taken substantially on the line 4—4 of Figure 1, illustrating the operating means for the latches of the upper sash.

Figure 5 is a detail horizontal section taken substantially on the line 5—5 of Figure 2, looking in the direction of the arrows, illustrating the keeper plate and openings for the holding latches of the lower sash.

Figure 6 is an enlarged detail fragmentary view, illustrating the means employed for holding the slide plates in a lowered position when the upper sash is swung into a room or removed from the window frame.

Figure 7 is a detail section taken on the line 7—7 of Figure 3, looking in the direction of the arrows, illustrating the means for holding the lower sash latches against unauthorized and accidental movement.

Figure 8 is a detail fragmentary view showing the inner face of one of the slide plates.

Figure 9 is a side elevation showing the lower end of one of the slide plates with its foot for detachably supporting the upper sash, the sash being shown in dotted lines.

Figure 10 is a view similar to Figure 3, illustrating a modified form of latch for holding the lower sash in an adjusted position.

Figure 11 is a detail horizontal section taken on the line 11—11 of Figure 10.

Figure 12 is a detail horizontal section through one end of one of the latch arms taken on the line 12—12 of Figure 10, looking in the direction of the arrows.

Figure 13 is an enlarged, fragmentary longitudinal section through the lower end of the window frame, illustrating a modified form of

means for holding the slides carrying the upper sash in an adjusted position.

Figure 14 is a detail horizontal section through the frame, taken on the line 14-14 of Figure 13, illustrating the operating means for the holding lever for the upper sash slide plates.

Figure 15 is a detail vertical section taken on the line 15-15 of Figure 13, illustrating the means utilized for preventing outward movement of the slide plates when the same are in their extreme lowered position.

Figure 16 is a detail vertical section taken substantially on the line 16-16 of Figure 13.

Figure 17 is a detail horizontal section taken on the line 17-17 of Figure 6, looking in the direction of the arrows.

Referring to the drawings in detail, wherein similar reference characters designate corresponding parts throughout the several views, the letter F generally indicates a window frame in which is mounted an upper sash 10 and a lower sash 11.

In general, the window frame F and the sashes 10 and 11 are of ordinary construction, and thus the window frame F includes the side stiles 12, the lintel 13, and the sill 14. Each of the sashes include the usual side, top, and bottom rails, which are constructed to receive and hold the window panes.

The inner faces of the stiles 12 of the window frame F can be provided with a filler or guide strip 15 and a blind stop or strip 16. The filler or guide strip 15 extends from the extreme top of the window frame to the sill. This top sash is of a less width than the bottom sash, as can be seen by referring to Figure 1 of the drawings, and passes freely between the filler or guide strips 15.

Any preferred means can be provided for normally holding the top sash in its raised elevated position, such as sash weights and cords. In the present instance, I have illustrated the use of thin metallic bands 17, which are adapted to be wound off and on spring drums carried by the window casing. The lower ends of these metallic bands 17 carry the slides 18 upon which the top sash 10 rests, as will now be set forth.

In lieu of connecting the spring bands 17 or the sash cords directly with the top sash, I utilize the novel slides or plates 18 on each side of the window. These slide plates are of substantially the same length as the top sash, and the same can each be formed from a single piece of sheet metal folded into the desired form.

Each slide plate 18 includes inner and outer walls 19 and 20 connected by a rear wall 21. The outer wall 20 is folded at right angles, and is then bent back in parallel relation to the inner and outer walls, as at 22. This forms a reinforcement and a guide, as will be later set forth. The inner side wall 19 is provided with an in-turned flange 23, which is arranged in spaced relation to the bent back portion 22, defining in connection therewith a guide slot 24. The wall 19 of each slide plate is cut away at the top for the reception of the sash cord or metallic strip 17, and this cutaway portion allows the free sliding of the slide plates past the cord pulleys when such is utilized. Suitable means such as a screw or pin 25 is provided for anchoring the lower ends of the sash cords or strips 17 with the slide plates. When the slide plates are in their raised position, the same are confined against lateral shifting movement by the stop strip 16 and the filler strip 15. The lower ends of the outer walls 20

of the slide plates have formed thereon inwardly extending supporting feet 26, on which the lower corners of the upper sash 10 normally rest.

When the upper sash is lowered and moved past the lower ends of the weather strips 27 carried by the filler strips 15, the sash can be swung into the room, or can be quickly lifted off of the feet 26 so that the opposite faces of the window pane can be conveniently and expeditiously cleaned. This also facilitates the assembling of 10 a window.

When the top sash is in its swung open position, or is removed from the frame, means is provided for automatically holding the slide plates in their lowered position. This means includes 15 rocking latches 28 located within and carried by the slide plates. The lower outer corners of the latches 28 are provided with noses 29, which are loosely mounted within openings 30 formed in the rear wall 21 of the slide plates 18, so that the 20 said latches can swing back and forth in the slide plates.

In view of the fact that the upper ends of the latches are at one side of the noses 29, the latches normally tend to swing down and out of the slide 25 plates, and under the lower ends of the weather strips 27 for engagement therewith. When the latches swing under the weather strips, upward movement of the slide plates will be prevented, as the latches engaging the weather strips 30 resist said upward movement.

The swinging movement of the latches 28 is limited by outwardly extending pins 31 carried by the upper ends of the latches. These pins work back and forth in slots 32 formed in the 35 slide plates and protruding a considerable distance beyond the inner faces of the slide plates.

The outer ends of the pins 31 are arranged in the path of the upper sash, and consequently when the upper sash is swung into a vertical 40 position, the sash will engage the pins and move the latches 28 away from underneath the weather strips 27, thus permitting the free sliding movement of the slide plates and the top sash.

The weather strips 27 are formed from sheet 45 metal and are folded back upon themselves to define an outwardly extending rib, and the edges of the rib are adapted to be inserted within suitable slots within the window frame.

Novel means is provided for holding the upper 50 sash in any adjusted open position, and in its closed position. This means includes a spring-pressed latch bolt 33 carried by one side of the window frame. The latch bolt 33 is normally urged out of the frame toward one edge of the 55 top sash, and this edge is provided with a rack bar, or a series of openings 34 for receiving the bolt. The rear end of the bolt has formed thereon an eye 35 through which extends one end of a bell crank shaped lever 36. This lever, at its 60 angle, bears against the window frame and rocks thereon, and the lower end of the lever is connected to a slide block 37 carried by the front 65 of the window frame. This slide block is provided with a finger-piece 38. Obviously by manipulating the slide block the latch bolt can be moved out against the tension of its spring.

Particular attention is now directed to the lower sash 11, and while this sash can be made to slide up and down, I prefer to have the same 70 simply set into the frame for swinging movement. Hence, no stop strip is provided for the lower sash. The inner faces of the stiles of the window frame can carry, however, weather strips 39, the ends of which are also preferably set into slots 75

in the window frames. The weather strips 39 are folded to provide front ribs 40, which extend out parallel to the inner faces of the stiles for fitting in grooves 41 in the lower sash. These strips 39 are further folded to form rearwardly extending ribs 42 (see Figure 7), to fit in the guide slots 24 of the slide plates 18, when the same are in their lowered position.

The window sill can carry a resilient piece of weather stripping 43 against which the lower rail of the bottom sash can rest.

To permit of the holding on the lower sash in an adjusted swung open position, the sides of the stile carry keeper plates 44. The keeper plates have a row of keeper openings 45 therein. The openings 45 are formed relatively deep, and the keeper plates immediately above the row of deep keeper openings are provided with a single shallow keeper opening 46. The side rails of the lower sash 11 each carry outwardly spring-pressed latch bolts 47. When the sash is in its closed position, the bolts are adapted to engage the innermost of the keeper openings 45, and when the sash is swung open the latch bolts 47 can engage 25 in either one of the other openings 45.

A single means is provided for operating the latch bolts 47, and the same may consist of an angle-shaped operating lever 48, pivoted at one end on a pin 49 carried by the sash. The outer 30 end of the lever extends beyond the upper face of the top rail of the sash, and has formed thereon a finger-piece 50. Rockably connected to the lever, at its angle, are oppositely extending bell crank shaped levers 51. These levers 51 are received in slots on the window sash, and are pivoted at their angles on pins 52 carried by the sash. The lower ends of the levers 51 are operatively connected to the latch bolts 47. Consequently, upon upward swinging movement of the 35 operating lever 48, the latch bolts can be moved inwardly against the tension of their springs, and away from the keeper plates 44.

In order to prevent the unauthorized operation of the latch bolts 47, by persons on the outside of the window, when the window is in a partially open position, I provide a spring-pressed push rod 53. This push rod 53 is carried by one side rail of the lower sash, and is disposed at right angles to the adjacent latch bolt 47. A transverse slot 54 is formed in the push rod, and normally this slot is out of alignment with the adjacent lever 51. When it is desired to manipulate the latch bolts 47, the operator presses inwardly upon the push rod 53 until the groove 54 aligns with the lever 51, and when this takes place the lever can move into its fullest extent, allowing proper manipulation of the latch bolts.

In some instances, it may be desirable to remove the lower sash and reverse the position thereof, so that the sash can be held rigid during the washing of its normally outside face. This can be easily accomplished by simply lifting the sash from the window frame and reversing the position thereof. When the position of the lower sash is reversed, the latch bolts 47 are disposed in the path of the keeper socket or opening 46, and consequently the latch bolts 47 will ride therein and hold the lower sash solid. As this opening 46 is of a shallow depth, the bolts will not move outwardly for a very great distance, and consequently a lever 51 will still be in the slot 54 of the push rod 53. This will permit manipulation of the latch bolts without further operation of the push rod.

In Figures 10 and 11 I have illustrated a slightly

modified form of latch for holding the lower sash in its completely closed position or in its partially swung open position. In these figures the lower sash is generally indicated by the reference character 60, and, as shown, the same includes the side rails 61 and the top rail 62. The outer edges of the side rails 61 are slotted, as at 63, to receive the operating levers 64, which are rockably mounted intermediate their ends on pivot pins 65 carried by the sash rails.

The lower ends of the levers 64 have formed thereon or secured thereto outwardly extending latch noses 66, which are adapted to engage keeper plates on the sides of the window frame. These plates can be the same as the plates 44 15 shown in Figures 2, 3, and 5.

The upper ends of the levers 64 are hooked through openings formed in the outer ends of actuating slide plates 67. The inner ends of these plates are arranged in over-lapping relation and are received within a metal guide 68 secured to the top or midrail 62 of the lower sash. These slide plates 67 are provided respectively with upstanding arms 69 and 70. The arms can be provided with removable finger-pieces 71.

As illustrated, the arm 69 extends through a slot 72 formed in the top slide plate 67. Leaf springs 73 are employed for engaging the lower ends of the levers 64 so as to normally urge the latch noses 66 into engagement with the keeper plates. Obviously, by moving the finger-pieces 71 toward one another, the levers 64 can be rocked so as to bring the noses out of engagement with the keeper plates. A finishing strip 74 is utilized for the top sash rail 62, so as to hide the 35 slide plates 67 from view, and this finishing strip can be slotted to receive the arms 69 and 70.

In Figures 13 to 16 inclusive, I have illustrated a modified form of means for holding the sides and, consequently, the upper sash in a locked adjusted position. This means can be utilized in lieu of the upper sash holding means illustrated in Figures 1 and 4.

As in the previous form, the slides for the upper sash are mounted between a parting strip 75 and an outer or blind stop 76. In Figures 13, 14, 15, and 16, the slides for the upper sash are generally indicated by the reference character 77, and the inner edge of one slide is provided with a series of spaced openings 78, the purpose 50 of which will be later set forth.

The parting strip or stop 75 has rockably mounted on its inner face by means of a pivot pin 79, a latch lever 80, and the upper end of this lever is offset, as at 81, to extend into a cavity 82 formed in the inner face of said parting strip 75. The upper end of the lever 80 has formed thereon a latch nose 83, which is adapted to extend through an opening 84 in the parting strip, whereby the nose can engage any one of the openings 78 in the sash slide 77. A leaf spring 85 is utilized for normally urging the nose 83 through the opening 84 toward the sash slide 77. The spring 85 has one end anchored to the window frame, and its other end bears against and is secured to the lever 80 above the pivot point of said lever. The extreme lower end of the lever 80 has formed thereon a laterally extending arm 86, the inner end of which is provided with an eye 87. A push rod 88 is provided for engaging the eye, and this rod is mounted within a suitable casing 89 carried by the window frame. The outer end of the rod extends beyond the front face of the window frame and is provided with a manipulating finger-piece 90.

By pushing upon the finger-piece 90, the push rod will be operated for rocking the lever 80 on its pivot 79, and thereby swing the nose 83 away from its slide plate 77 against the tension of the spring 85, whereby the slide plates can be released to permit adjustment of the upper sash.

If preferred, the lower ends of each slide plate 77 below the supporting feet 91 for the upper sash can be provided with a depending lug 92, which is adapted to fit in rear of a stop piece 93 on the sill, when the upper sash and the slides are in their extreme lowered position. This prevents accidental outward swinging movement of the lower ends of the slides.

Referring back to Figure 10, in lieu of providing the latch noses 66, I can connect the lower ends of the levers 64 to latch bolts similar to the construction shown in Figure 3 of the drawings.

In Figures 13, 14, and 15, the weather strips 20 have been eliminated for the sake of clearness.

Changes in details may be made without departing from the spirit or the scope of my invention, but what I claim as new is:

1. In a window construction, slide plates having laterally extending feet on their lower ends, a sash freely removable from off of the supporting feet and between the slide plates, counterbalancing means for the sash connected with the slide plates, and means for detachably locking the sash in an adjusted vertical raised position.

2. In a window construction, slide plates having laterally extending feet on their lower ends, a sash freely removable from off of the supporting feet and between the slide plates, counterbalancing means for the sash connected with the slide plates, and means for detachably locking the sash in an adjusted vertical raised position, said means including a rack bar carried by one edge of the sash, a spring pressed bolt carried by the frame for engaging the rack bar, and means for manipulating the bolt.

3. In a window construction, a window frame, an upper sash slidably mounted in the frame and freely removable therefrom when the sash is in its lower position, a bottom sash freely removable from said frame, the lower edge of the bottom sash being rockable upon the sill, latch plates carried by the sides of the window frame, lateral extending spring-pressed bolts carried by the lower sash for engaging in any one of a plurality of keeper openings carried by the latch plates, means for simultaneously operating the latch bolts, and manual operable means normally preventing operation of the latch bolts.

4. In a window construction, a window frame, an upper sash slidably mounted in the frame and freely removable therefrom when the sash is in its lower position, a bottom sash freely removable from said frame, the lower edge of the bottom sash being rockable upon the sill, keeper plates carried by the sides of the window frame, lateral extending spring-pressed bolts carried by the lower sash for engaging in any one of a plurality of keeper openings carried by the plates, means for simultaneously operating the latch bolts, and manual operable means for normally preventing operation of the latch bolts, said means including a push rod located intermediate the ends of the lower sash and disposed in the path of movement of a part of the operating mechanism for said latches.

5. In a window construction, a window frame, a bottom sash freely removable from the frame and rockably mounted upon the sill of the frame, keeper plates carried by the sides of the window frame, latch members carried by the sides of the sash for engaging the keeper plates, levers rockably mounted intermediate their ends in the side rails of the sashes operatively connected to the latch members, operating slide plates carried by the top rail of the lower sash operatively connected to the upper ends of the levers, the inner ends of the slide plates being arranged in overlapping relation, a guide carried by the sash for the overlapping ends of the slide plates, and operating finger-pieces carried by the overlapping ends of the slide plates.

6. In a window construction, slide plates having laterally extending feet on their lower ends for detachably supporting the lower end of a sash, and means for detachably locking the sash in an adjusted position including a plurality of keeper openings formed in one of the slide plates, a latch lever rockably carried by the window frame having a nose for engaging in any one of said keeper openings, spring means normally urging the nose toward a slide plate, and a push rod extending out of the frame for operating said lever.

7. In a window construction, slide plates having laterally extending feet on their lower ends for detachably supporting a sash, a window frame having a guide for the slide plates, a depending lug on the lower end of each slide plate below the feet, and a holding member carried by the sill of the frame for engaging the lug when the slide plates are in their lowered position.

CHARLES W. TINGLEY.
